UNITED STATES PATENT OFFICE.

ESTHER H. SWETLAND, OF NORTH TONAWANDA, NEW YORK.

DESIGN FOR A TOY.

50,853.

Specification for Design.

Patented May 29, 1917.

Application filed April 3, 1917. Serial No. 159,555. Term of patent 7 years.

To all whom it may concern:

Be it known that I, ESTHER H. SWETLAND, a citizen of the United States of America, residing at North Tonawanda, in the county of Niagara and State of New York, have invented a new, original, and ornamental Design for a Toy, of which the following is a specification, reference being had to the accompanying drawings, forming part hereof.

In the drawing

The figure is a perspective view of a toy showing my new design.

I claim—

The ornamental design for a toy as shown.

ESTHER H. SWETLAND. [L.S.]
